ATTORNEY

UNITED STATES PATENT OFFICE.

ARNOLD HOERMANN, OF HOBOKEN, NEW JERSEY.

T-SQUARE.

SPECIFICATION forming part of Letters Patent No. 248,652, dated October 25, 1881.

Application filed August 5, 1881. (No model.)

To all whom it may concern:

Be it known that I, ARNOLD HOERMANN, of Hoboken, in the county of Hudson and State of New Jersey, have invented certain new and 5 useful Improvements in T-Squares, of which the following is a specification.

The object of this invention is to furnish for office and school purposes an improved T-square the blade of which can be adjusted to 10 any desired angle by a simple and reliable mechanism without the use of a clamping-screw; and the invention consists of a T-square the blade of which is fitted by a conically-tapering pivot-plate into a correspondingly-tapering recess of the head, and tightly secured 15 in position thereon by means of a clamping lever-plate, which engages, by interior radial ribs, inclined cheeks of a plate secured to the under side of the head.

20 In the accompanying drawings, Figure 1 represents a plan view of my improved T-square. Fig. 2 is a vertical central section of the same on line $x-x$ of Fig. 1; and Figs. 3 and 4 are detail views, respectively, of the 25 clamping lever-plate and of the bottom plate of the head of the T-square.

Similar letters of reference indicate corresponding parts.

Referring to the drawings, A represents the 30 head, and B the blade, of my improved T-square. The blade B is pivoted to a central perforation of the head A by means of a pivot-plate, C, which is secured to the under side of the blade by suitable screws, rivets, or otherwise. The circumference of the pivot plate C 35 is conically beveled and fitted into a correspondingly-beveled recess, a , of the head A. To the under side of the head A is secured a plate, D, having two or more inclined cheeks, 40 d ; along which the interior radial ribs d' of a clamping lever-plate, E, are moved when the same is turned on the center-pivot b of the plate C. The lever-plate E turns loosely on the shank of the fastening-screw e , which is 45 screwed into the pivot of the plate C, a spiral or flat friction-spring, f , being preferably interposed between the pivot-plate C and the recess

50 a of the head of the T-square for preventing any rattling, though for the cheaper kind of T-squares this spring may be dispensed with. 55 By turning the lever-plate E in one direction the interior ribs of the same move upon the inclines of the bottom plate, D, and serve to draw the blade B into frictional contact with the conical recess of the head, so as to secure 60 it tightly and reliably in any desired position thereon. By moving the lever-plate in the opposite direction the blade is released for adjustment on the head. In the better classes of T-squares a graduated scale may be arranged on 65 the head, so as to set off any desired angle by means of a pointer secured to the end of the blade.

For the cheaper styles of blades, such as are 70 used in school, I prefer to cast the pointer directly into the body of the conically-beveled pivot-plate, and use it in connection with a fixed index-point of the head for quickly setting and securing the blade at right angles to the head. By this construction a reliable adjustment of the blade to any desired angle may 75 be accomplished, the clamping mechanism having the advantage that all parts are of cast metal and not as liable to get out of order as the clamping-screws heretofore employed.

Having thus described my invention, I claim 75 as new and desire to secure by Letters Patent—

In a T-square, the combination of a blade having a conically-beveled pivot-plate fitting into a correspondingly-beveled recess or socket 80 of the head, with a fixed bottom plate, having inclined cheeks secured to the under side of the head, and with a centrally-pivoted clamping lever-plate having interior radial ribs moving along the cheeks of the bottom plate, substantially as described.

In testimony that I claim the foregoing as my invention I have signed my name, in presence of two witnesses, this 1st day of August, 1881.

ARNOLD HOERMANN.
